DESIGN FOR A FILLER BLOCK FOR SHOE DISPLAY

Edmund J. Baas, Rochester, N. Y.

Application August 16, 1937, Serial No. 71,139

Term of patent 7 years

To all whom it may concern:

Be it known that I, Edmund J. Baas, a citizen of the United States, residing at Rochester, in the county of Monroe and State of New York, have invented a new, original, and ornamental Design for a Filler Block for Shoe Display, of which the following is a specification, reference being had to the accompanying drawing, forming part thereof, and in which:

I claim:

The ornamental design for a filler block for shoe display as shown.

EDMUND J. BAAS.
